UNITED STATES PATENT OFFICE

142,947

DESIGN FOR A COMBINED BOTTLE HOLDER AND WARMER

Ervin J. Cain, Milwaukee, Wis.

Application February 1, 1945, Serial No. 117,711

Term of patent 14 years

(Cl. D81—10)

To all whom it may concern:

Be it known that I, Ervin J. Cain, a citizen of the United States, residing at Milwaukee, in the county of Milwaukee and State of Wisconsin, have invented a new, original, and ornamental Design for a Combined Bottle Holder and Warmer, of which the following is a specification, reference being had to the accompanying drawing, forming part thereof.

The figure is a perspective view showing the top and two sides of a combined bottle holder and warmer embodying my new design.

Inasmuch as the design is symmetrical when viewed from the front, the sides not shown have the same appearance as those illustrated, and the bottom is plain.

I claim:

The ornamental design for a combined bottle holder and warmer, as shown and described.

ERVIN J. CAIN.
